UNITED STATES PATENT OFFICE.

JEREMIAH KELLER, OF SANDUSKY, OHIO, ASSIGNOR OF ONE-HALF TO
EDWARD J. CABLE, OF SAME PLACE.

CHURN.

SPECIFICATION forming part of Letters Patent No. 359,978, dated March 22, 1887.

Application filed December 23, 1886. Serial No. 222,401. (No model.)

To all whom it may concern:

Be it known that I, JEREMIAH KELLER, of Sandusky, in the county of Erie and State of Ohio, have invented new and useful Improvements in Churns; and I do hereby declare that the following is a full, clear, and exact description thereof, reference being had to the accompanying drawings, which form a part of this specification.

10 This invention relates to certain new and useful improvements in churns.

The invention consists in the peculiar mechanism employed for partially rotating parallel dashers in opposite directions, and in the peculiar construction, arrangement, and combination of the various parts, all as more fully hereinafter set forth.

Figure 1 is an elevation of my improved churn. Fig. 2 is a perspective view of the 20 operating parts removed from the churn-body.

In the accompanying drawings, which form a part of this specification, A represents a churn-body provided with a removable top or cover, B, and arranged to be rigidly secured 25 upon such churn, when in use, by hooks or other suitable devices (not shown) for the purpose.

C are two vertical and parallel shafts or dash-rods, properly journaled through the head 30 B, their upper ends finding bearings in the standards D, rising from the cover, and which also carry the actuating-lever E, fulcrumed between their upper ends, as shown.

F is a bow rigidly secured to the lever E, 35 and to each end of this bow is secured one end of two flexible straps, G, the opposite ends of such straps being rigidly secured to the vertical shafts C.

H is another flexible strap, the ends of which 40 are secured to the vertical shafts. These flexi-

ble straps are so connected to the shafts or dash-rods that as the lever E is oscillated such shafts are compelled to partially rotate in their bearings, the strap H being wound first upon one shaft and then upon the other, and aiding the straps G in rotating the said shafts, as will be readily understood. To the lower ends of the shafts C are secured the perforated beaters or dash-plates I.

In practice, the parts being arranged to operate substantially in the manner shown, it will be found that in the oscillation of the lever the beaters will be partially rotated in opposite directions, describing, as near as can be, in their movement a semicircle, and that this will necessarily continually agitate the churning, forcing the cream through the perforations and effectually separating the fatty globules from the milk.

I am aware of the patent issued to I. Van Gorder, June 27, 1832, and make no claim to the construction shown therein as forming part of my invention, but attach importance to my independent strap H, which aids the straps G in rotating the shafts C.

What I claim as my invention is—

The combination, with the parallel vertical shafts carrying beaters, of the standards D, lever E, fulcrumed thereon, bow F on said lever, the flexible strap H, having its ends secured to said shafts, and the flexible straps G, each having one end connected to said bow, and the opposite ends attached one to each of said shafts, substantially as and for the purpose specified.

JEREMIAH KELLER.
